US00D592753S

(12) **United States Design Patent**
Jacinto

(10) **Patent No.:** **US D592,753 S**
(45) **Date of Patent:** **** May 19, 2009**

(54) **PILLOW WITH OPENING FOR EAR**

(76) Inventor: **Louis Jacinto**, 16411 Lacey Blvd.,
Lemoore, CA (US) 93245

(**) Term: **14 Years**

(21) Appl. No.: **29/320,328**

(22) Filed: **Jun. 25, 2008**

(51) LOC (9) Cl. **24-02**

(52) U.S. Cl. **D24/183; D6/601**

(58) **Field of Classification Search** **D24/178,**
D24/183-184, 188, 190, 200; D6/595-599,
D6/601, 604; 5/630, 632, 636-639, 645,
5/648, 652, 655; 607/109; 297/452.1; 602/20;
128/845-846

See application file for complete search history.
